UNITED STATES PATENT OFFICE.

JAY GEARHART SHULENBERGER AND LEE WHITRIGHT, OF LODI, OHIO.

MAIL-BAG-DELIVERING DEVICE.

1,308,261.

Specification of Letters Patent.

Patented July 1, 1919.

Application filed September 29, 1915. Serial No. 53,173.

To all whom it may concern:

Be it known that we, JAY G. SHULENBERGER and LEE WHITRIGHT, citizens of the United States, residing at Lodi, in the county of Medina and State of Ohio, have invented certain new and useful Improvements in Mail-Bag-Delivering Devices, of which the following is a specification.

Our invention relates to improvements in mail bag delivering devices or apparatus and more particularly to an improved automatic mail crane whereby one or more mail bags are adapted to be held or suspended in proper position to be readily taken up by a passing car provided with the ordinary form of hook now in common use or other suitable and convenient device on the car.

The primary object is to provide a generally improved crane or mail bag delivering mechanism of exceedingly simple, cheap, and efficient construction by means of which one or more mail bags may be readily taken up and automatically released when engaged by the hook on a passing mail car without in any way injuring the mechanism or the mail bags or the contents thereof.

A further object is the provision of a post or pedestal having improved coöperating mail bag suspending levers or arms, together with improved suspending cable members detachably connected to the free ends of said levers or arms, said cable members also embodying improved bag and hook receiving loops, improved means being also provided for holding such hook receiving loop in open position as well as for maintaining the bag suspending cable members taut and in proper position until engaged and detached by the mail hook of the passing mail car.

A still further object is the provision of an improved mail bag suspending cable loop adapted to carry or suspend a plurality of mail bags without the necessity of engaging the latter directly by the hook of the mail car, such hook being adapted to pass into the hook receiving loop of the cable and detach such loop from the upper crane lever or bar.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings forming a part of this specification, Figure 1, is a side elevation of the improved mail bag delivering device or crane in its operative position properly holding and suspending a plurality of mail bags preparatory to receiving the hook of a passing mail car into the loop of the improved bag suspending cable and automatically detaching the same from the crane and delivering the mail to the car.

Fig. 2, a rear elevation of the same.

Fig. 3, a detail view of the crane post or pedestal.

Fig. 4, a detached detail view of one of the clamping plates used in connection with the bag securing and suspending loop of the cable members.

Fig. 5, a detail sectional view of such clamping plate in connected operative position with the cables and forming the double loop for receiving and supporting the mail bags.

Fig. 6, an enlarged detail side elevation of the clamping and detaching device for detachably connecting the bag suspending cables to the lower crane lever or arm.

Fig. 7, an enlarged detail view of the loop suspending and spreader heads at the free end of the upper crane arm or lever.

Similar numerals of reference designate like parts throughout all the figures of the drawings.

The improved mail bag delivering device or crane comprises a suitable pedestal or crane post 1, adapted to be mounted and supported in a suitable manner at a suitable distance at one side of the railway track, said post or pedestal, in the present instance, comprising two members suitably connected and spaced apart and being provided with upper and lower mail bag suspending levers or arms 2 and 3, respectively.

The upper and lower levers or arms 2 and 3, are provided with weights 2^a and 3^a, respectively, whereby the free or inner ends of the vertically swinging arms will be caused to move away from each other or upwardly and downwardly when the improved mail bag suspending cable members are detached as hereinafter explained; and whereby when said mail bag suspending cable members are in their normal or operative position as shown in Figs. 1 and 2, of the drawings, such cable members will be maintained taut and held in proper position for the detach-

ment and delivery of the mail matter as hereinafter more fully referred to.

As a means of holding the upper crane arm 2, in its horizontal or mail bag suspended position said arm is provided near its pivoted portion with a pawl or dog 2^b, adapted to rest on a cross bar or support 1^b, at the upper end of the crane post 1.

As a means of properly holding and suspending the mail bag suspending cable loop in position to receive the hook of the passing car, the free end of the upper lever is provided on opposite sides with loop suspending spreader heads 4, to removably receive and carry under tension the spaced apart members of the mail bag suspending cables to be now described.

The spreader heads 4, are semi-circular shaped and provided on their curved or upper sides with cable receiving grooves so that the cable loops will not become accidentally removed or displaced.

The improved mail bag suspending cable comprises, in the present instance, a single length of cable folded upon itself midway of its ends to form a hook receiving loop 5, (adapted to be mounted upon one or the other of said spreader heads 4, in accordance with the direction in which the mail car is to pass) said mail bag suspended cable being formed into a bag engaging and suspended loop 6, adapted to carry one or more mail bags 7, and as a means of securely retaining the loop 6, in adjusted position the ends of the cable are connected to guide or slip plates 8, (see Figs. 4 and 5) the outer ends of said plates being provided with inclined or obtusely angled openings 8^a, to receive and pass over the intermediate portions of the cable, and when adjusted, being adapted to crimp into the cable members and hold the latter from slipping or loosening about the mail bags 7.

As a means of detachably connecting the bag engaging and suspending loop 6, of the cable to the lower arm or lever 3, the latter is provided with a cable clamping and detaching device, said device, in the present instance, being connected to the free end of the lever 3, by means of a second cable 9, and consisting, in the present instance, of two pivoted members 10, normally held together by means of a spring 10^a, the curved jaw portions 10^b, thereof being adapted to resiliently engage and carry the lower end of the loop 6, when the latter is carrying the mail bag 7, as shown in Figs. 1 and 2 of the drawings.

When the jaws 10^b, of the clamping device are in engagement with the loop 6, it will be obvious that the weight 3^a, on the end of

the lever 3, will maintain the mail bag suspending cable members in a substantially vertical position and will prevent the suspended mail bags from being swung laterally and it is equally obvious that when the hook of a passing mail car engages in and carries off the loop 5, from the adjacent spreader head 4, the spring 10^a, will permit the jaws 10^b, to spread and release the loop 6, carrying the mail bags 7.

It will also be observed that since the mail or bag hook carried on the mail car does not come into direct contact with the mail bags 7, it cannot injure the latter or the contents thereof, and furthermore less shock or impact is transmitted to the bags and mail matter because such bags are suspended and permitted to freely swing as the car mail hook carries them off.

As such car or bag engaging hook is well known and understood and as such or any other car attachments form no part of the present invention, it need not be shown or described in detail in this application.

From the foregoing description, taken in connection with the accompanying drawings, the operation and advantages of our invention will be readily understood.

Having thus described one of the embodiments of our invention, what we claim and desire to secure by Letters Patent, is,—

1. In a mail bag delivering device, a single length of cable folded upon itself forming a hook receiving loop at one end and a double mail bag receiving and suspending loop at the other, the members of the latter being each provided with a slip plate adjustably clamping said cable below said hook receiving loop.

2. In a mail bag delivering device, a single length of cable folded upon itself forming bag and hook receiving loops said bag receiving loop comprising two members having adjustable clamping devices consisting of a pair of perforated slip plates engaging the intermediate portions of said cable.

3. In a mail bag delivering device, a pedestal provided with upwardly and downwardly swinging weighted levers, and bag suspending cables detachably suspended therebetween and detachably connected to each other, one of said cables having adjustable bag and hook receiving loops.

In testimony whereof we have affixed our signatures in the presence of two witnesses.

JAY GEARHART SHULENBERGER.
LEE WHITRIGHT.
